UNITED STATES PATENT OFFICE.

ERNEST CHAPIN COLE, OF CHICAGO, ILLINOIS, ASSIGNOR TO COLE MANUFACTURING COMPANY, OF CHICAGO, ILLINOIS, A CORPORATION.

ASH-DOOR.

SPECIFICATION forming part of Letters Patent No. 752,522, dated February 16, 1904.

Application filed October 6, 1903. Serial No. 175,958. (No model.)

To all whom it may concern:

Be it known that I, ERNEST CHAPIN COLE, a citizen of the United States, and a resident of Chicago, in the county of Cook and State of Illinois, have made certain new and useful Improvements in Ash-Doors, of which the following is a specification.

My invention is an improvement in stoves, and particularly in the construction of the draft or ash-pit door; and the invention has for an object to provide a novel construction of connection between the stove-section and the cover-section of such door, whereby the cover-section can be conveniently applied to and removed from the stove-section and will be properly hinged in connection therewith when applied, and to so construct the parts that the fitting or bearing surfaces between the cover-section and the stove-section can be conveniently ground on emery or other grinding wheels to a true surface; and the invention consists in certain novel constructions and combinations of parts, as will be herein-after described and claimed.

In the drawings, Figure 1 is a perspective view of a portion of a stove provided with my invention. Fig. 2 is a detail vertical section drawn through the door of the stove. Fig. 3 is an elevation of the inner side of the joint between the stove-section and the cover-section with the pintle of the hinge in engagement with the stove-section, as in the use of the device. Fig. 4 is an elevation similar to Fig. 3, showing the position of the hinge-pintle in connecting and disconnecting the two sections; and Fig. 5 is a plan view of the inner side of the cover-section.

For convenience of reference I term the sections A and B of my invention, respectively, the "stove-section" and the "cover-section," as the former is secured to the body of the stove and the latter operates to close the opening *a* in the section A. This section A curves upwardly toward its upper outer end *a*, the latter being formed at an incline, so the cover B will drop and rest thereon by gravity. Above the opening *a* I provide the section A with the knuckle A' of the hinge between the sections A and B. It will be noticed, espe-

cially from Fig. 2, that the knuckle and the parts immediately connected therewith are so remote from the opening *a* that the latter may be ground to the desired surface upon an emery or similar wheel without any abrasion of the knuckle A', as will be understood from dotted lines in Fig. 2, which dotted lines represent a portion of an emery-wheel in contact with the open end *a* of the section A. It is well understood that emery-wheels usually get worn a little rounding or irregular at their outer edges and cannot be relied on to make a close ground surface to their outer edges, and it therefore becomes desirable to provide for some considerable projection of the emery-wheel beyond the surface to be ground, so the fourteen or eighteen inch circular emery can be applied flatwise to the surfaces to be ground, as indicated in dotted lines, Fig. 2, without coming in contact at its edges with any projecting portions of the construction to be ground. For this reason I avoid the provision of any projection on the section A adjacent to the surface *a* to be ground, so the latter can be conveniently ground on an emery-wheel, although the edges of the latter are rounded or irregular, as before referred to.

The knuckle A' is of a special construction, being arched outwardly at *a'*, forming the recess *a''* within it to receive the pintle *b* of the section or lid B and to permit the operation of such pintle, as will be described. The knuckle A' is also provided with a vertically-elongated opening *a'''* and at the base thereof with a ledge or shoulder at *a''* for engagement by the projecting lug *b'* at the middle of the pintle *b*. The pintle *b* is carried on the arm B', projecting at one edge of the lid B, and the pintle *b* projects equally on the opposite sides of the said arm B' and the arm B'', and the pintle and its lug *b'* are so formed that the pintle may be passed through the slot *a'* in the knuckle A' in both inserting and removing the said pintle by turning the pintle to a position diagonal to the length of the slot *a'*, as shown in Fig. 4, so the pintle can be readily passed through the said slot and then turned to the position shown in Figs. 2 and 3 to permit it to rock in opening and closing

the lid B. When it is desired to hold the lid open, such lid may be raised to the position shown in Fig. 2 and then lifted to permit its projecting lug b' to engage with the shoulder 5 a' of the knuckle A', when the lid will be supported in the position shown in Fig. 2.

- It will be noticed that the arm B' projects away from the inner surface C of the section or lid B, and this latter surface C may be 10 ground upon the flat side of an emery-wheel without such wheel coming in contact with the projecting hinge-arm B' of the lid, as will be understood from Fig. 2 of the drawings. The lid B may have an opening D, closed by 15 the cap E, the latter being secured by the screw-stud E', turning in the bar E², which crosses the opening D in the lid or section B, as will be understood from Figs. 2 and 5 of the drawings.
- 20 It will be noticed that the construction shown avoids the necessity of any hinge-studs close to the surface to be ground and dispenses with any separate hinge-pins. It will also be noticed that the cover may be removed 25 from and applied to the stove section or elbow only by twisting or turning the said lid to a certain position. This interlocking of the lid and body or stove section is important and it will be understood that various other means 30 of securing the same result might be provided, and I do not desire to be limited in this broad feature of my invention to the special construction shown, although I prefer to employ the construction shown, as it furnishes a 35 strong frame that will not easily break in handling and milling and permits the use of a small emery-wheel in bringing the surfaces to the desired shape.
- It will be understood that the purpose of the 40 special construction shown is to provide an ash-pit or draft door with projecting surfaces in which both sections can be easily ground to a perfect fit on an ordinary emery-wheel, sufficient space being left between the edges to 45 be ground and the necessary hinge projections to permit the grinding to a perfect fit, as desired. The lid can be lifted for removing ashes, and its weight will allow the lug b' to engage with the stove-section and hold the lid 50 elevated, and the lid can be closed by slightly lifting it and permitting it to drop to closed position, as shown in Fig. 1.

Having thus described my invention, what I claim as new, and desire to secure by Letters Patent, is—

55

1. The improvement in ash-pit or draft doors for stoves substantially as herein described comprising the body or stove section having an upwardly-inclined elbow portion whose outer or open end is inclined and provided with a hinge-knuckle sufficiently remote from the open end to permit the grinding of the latter without abrading the knuckle portion said knuckle having the outwardly-rounded portion provided with the slot for the pintle 60 and with the shoulder at the base of said slot and the lid or cover-section fitted to the open end of the body-section and provided with the projecting hinge-arm having the pintle and the lug projecting therefrom, said pintle being 65 adapted to fit within and engage with the knuckle of the body-section and to be passed through the slot in said knuckle when shifted to a position diagonal thereto, in applying and removing the lid substantially as and for the 70 purpose set forth.

2. The combination in an ash-pit or draft door with the stove-section having a hinge-knuckle provided with a slot for the passage of the pintle and with a recess in rear of said slot 80 for the operation of such pintle, and the lid or cover having the hinge-arm and the pintle thereon, said pintle being formed to engage with the knuckle of the door-section and to be passed through the slot in said knuckle when 85 disposed diagonally thereto in connecting and disconnecting the sections substantially as set forth.

3. The combination in an ash-pit or draft door of the body or stove section having an 90 inlet-opening and a hinge-knuckle having a slot for the passage of the pintle and a shoulder for engagement by the lug thereon, and the lid or door having a pintle to operate in the knuckle of the stove-section and a projecting lug to engage with said section, the knuckle being formed to pass through the slot in the knuckle-section when disposed diagonally thereto substantially as and for the purpose 95 set forth.

ERNEST CHAPIN COLE.
